UNITED STATES PATENT OFFICE.

CHARLES H. DANIELSON, OF FALLOON, NEVADA.

DESIGN FOR A COMBINED RING AND LOOP FOR HARNESS.

42,731.

Specification for Design.

Patented July 9, 1912.

Application filed October 3, 1911. Serial No. 652,661. Term of patent 14 years.

To all whom it may concern:

Be it known that I, CHARLES H. DANIELSON, a citizen of the United States, residing at Fallon, in the county of Churchill and State of Nevada, have invented a new, original, and ornamental Design for a Combined Ring and Loop for Harness, of which the following is a specification, reference being had to the accompanying drawing, forming part thereof.

The figure is a perspective view of a combined ring and loop for harness, showing my new design.

I claim:

The ornamental design for a combined ring and loop for harness, as shown.

CHARLES H. DANIELSON.

Witnesses:

ARCH MOON,
WILLIAM S. WALL.
